US00D649283S

(12) **United States Design Patent**
Wegscheider

(10) **Patent No.:** **US D649,283 S**
(45) **Date of Patent:** **** Nov. 22, 2011**

(54) **ACCESSORY FOR A LAMP**

(75) Inventor: **Martin Wegscheider**, Wattens (AT)

(73) Assignee: **Swarovski Aktiengesellschaft**, Triesen (LI)

(**) Term: **14 Years**

(21) Appl. No.: **29/393,578**

(22) Filed: **Jun. 7, 2011**

(30) **Foreign Application Priority Data**

Jan. 27, 2011 (EM) 001256887-0001

(51) **LOC (9) Cl.** **26-99**

(52) **U.S. Cl.** **D26/154**

(57) **CLAIM**

The ornamental design for an accessory for a lamp, as shown and described.

DESCRIPTION

FIG. 1 is a perspective view of the invention;

FIG. 2 is a top view of the invention;

FIG. 3 is a front view of the invention;

FIG. 4 is a right side view of the invention;

FIG. 5 is a rear view of the invention;

FIG. 6 is a bottom view of the invention;

FIG. 7 is a left side view of the invention; and,

FIG. 8 is a cross-sectional view of the invention showing a through-hole.
